Primary Examiner — Philip S Hyder*Assistant Examiner* — Darlington Ly(74) *Attorney, Agent, or Firm* — Che-Yang Chen; Law Office of Michael Chen(57) **CLAIM**

The ornamental design for a tool sleeve, as shown and described.

DESCRIPTION

FIG. 1 is a perspective view of a tool sleeve showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view thereof, wherein the plane at which the section is taken is reference as 8-8 in FIG. 6. The broken lines shown in the drawings illustrate portions of the tool sleeve that forms no part of claimed design.
